COMB-BARRETTE

Harry Moses, Brooklyn, N. Y.

Application March 4, 1948, Serial No. 13,010

1 Claim. (Cl. 132—48)

1

This invention relates to combs; relates particularly to barrette combs; and relates especially to combinations of barrettes and combs having means for fastening them into the wearer's hair.

Among the more usual feminine ornaments are barrettes or hair combs of a wide variety of patterns which are thrust into the wearer's hair and are supposed to be held in place by the action of various styles of clamps or by action of the hair strands on the teeth of the comb. This holding action is, however, poor, and combs are quite insecurely held, especially when they have elaborate decorative portions.

The present invention provides a combination comb and barrette structure in which there is a spring-held fastening means adapted to engage auxiliary strands of the wearer's hair to hold the barrette and comb combination firmly in place, while at the same time the holding means is concealed, partly within the structure of the comb, and partly by the wearer's hair.

This object is attained by the provision of a tubular member forming a portion of the comb-barrette combination within which there is positioned an elastic tensioning means and portions of one or more U-shaped spring clamping members which engage strands of the wearer's hair, holding it against the back of the comb body, the U-shaped locking members being held by the elastic tension means, and, if desired, by locking means on the outer surface of the comb body.

Thus the invention provides a combination comb and barrette having teeth at the bottom thereof, a tubular body member, to which there may be attached, if desired, a decorative element, within which body there is positioned an elastic tension means cooperating with arcuate clamp members drawn against and into the body by the tensioning means, with exterior locking means, if desired. Other objects and details of the invention will be apparent from the following description when read in connection with the accompanying drawings, wherein

Fig. 1 is a front view of the comb structure;

Fig. 2 is a side view in section of the same structure;

Fig. 3 is a top view in section of the same structure;

Fig. 4 is a back view of the comb structure showing the clamp means and locking means; and

Fig. 5 is a view of the comb in position in a wearer's hair.

The structure of the invention consists of a body member 1 which is preferably tubular in form and of a suitable length to form a barrette.

2

To the barrette body member 1 there is then attached a comb portion 2, and, if desired, a decorative member 3 which may take any form desired with a wide variety of decorative elements such as glass brilliants, imitation pearls, moulded insignia, and, in fact, any of the standard decorative elements. Within the tubular body member 1, there is positioned one or more arcuate members 4 equipped with fastening means, to which there is attached an elastic tension member 6. This tension member may take the form of a rubber strip, or may take the form of a metal spring or other type of tension member, as desired. It is usually preferable that the tension member 6 be capable of considerable elongation, to permit of withdrawal of the arcuate members 4 nearly out from the tubular body member 1.

It is usually convenient to provide two of the members 4, but this is not essential since the elastic member 6 may be anchored to a suitable holding means within the body member 1, and a single arcuate member 4 may then be used. Alternatively, the body member 1 may contain two or more tubular portions, in each of which there may be provided one or two arcuate members 4, as desired. By this means a considerable range of security of fastening is obtainable. Also, the outer ends of the arcuate members 4 may be perforated with holes 7 cooperating with pin members 8 to provide still firmer locking means.

In the operation of this invention, the comb teeth 2 which may take any desired form or length, are inserted in the wearer's hair, the comb being placed in any desired position. Thereafter, at least one of the arcuate members 4 is pulled out from the body 1 against the tension of the member 6 and then allowed to retract under the pull of the member 6 with the outer end enclosing a substantial number of strands of the wearer's hair. When the member 4 has been fully retracted into the comb body 1, the outer end may be locked over the pin member 8. This procedure may be repeated with each of the additional arcuate members 4 until a solidly fastening situation is produced. This procedure holds the comb-barrette combination firmly in place in the wearer's hair and makes the best possible display of the decorative portion 3 which can be had (if such is used), and the various members stay firmly in place through almost unlimited amounts of physical activity on the part of the wearer.

Thus, the device of the invention provides a comb-barrette combination having spring-held and doubly-spring-held locking means holding the comb structure solidly in and on a wearer's hair.

A series of holes 9 are provided in the body member 1 and an absorbent member 10 is positioned back of the holes. This member serves as a convenient means for carrying a supply of perfume which may evaporate through the holes 9 yielding a continuing supply of pleasant aroma under circumstances where the rate of evaporation is low and a small supply maintains a perfumed state for a prolonged period of time.

Thus the invention provides primarily a body having a plurality of U-shaped clamps with one leg of each drawn into the tubular body by a spring member to provide a primary fastening means for the body, with comb tooth members attached to the body entering a wearer's hair to provide a second means for holding the structure in a wearer's hair. It may be noted that the body 1 and the comb teeth 2 with the clamps, as described, may be used to form a simple comb-barrette combination, with such decorations on the body 1 as may be desired. Alternatively, and within the scope of the invention, such auxiliary and additional decorative members as are desired may be attached to the body 3 either along the face of the body or along the upper portion thereof, as desired.

While there are above disclosed but a limited number of embodiments of the device of the invention, it is possible to provide still other embodiments without departing from the inventive concept herein disclosed, and it is therefore desired that only such limitations be imposed upon

the appended claim as are stated therein or required by the prior art.

The invention claimed is:

A comb structure having teeth and a back, said back comprising a tubular structure attached to said teeth and forming part thereof; a pair of substantially U-shaped resilient hair clip members cooperating with said tubular member, each having two extensions, one positioned within the said hollow back and the other positioned outside of the hollow back, and a tension member attached to said extensions within said tubular structure, whereby said hair clip members are elastically positioned to grip a wearer's hair against said tubular member, and catch members on the outer rear side of said tubular structure cooperating with perforations located in the said extensions outside of the hollow back, to lock said extensions in place.
